**SOLID-STATE CIRCUIT BREAKER THAT
TURNS OFF ELECTRONICS BEFORE
PRIMARY MAIN CONTACTS ARE OPENED**

BACKGROUND

1. Field

Aspects of the present invention generally relate to a solid-state circuit breaker includes a secondary switch to turn off electronics before a pair of opposing primary main contacts are opened.

2. Description of the Related Art

In a circuit breaker, the main contacts are usually made of silver alloy and conduct current in closed positions.

When the contacts are parted, an arc is produced. Arcing occurs whenever current is interrupted with contact separation. With the extreme temperature of arcs, they can cause erosion to the contacts and damage to the circuit breakers, and eventually lead to end of life of a circuit breaker.

The best way to avoid such erosion is to eliminate or significantly reduce arcs during current interruption.

Therefore, there is a need for a better solid-state circuit breaker.

DETAILED DESCRIPTION

Various technologies that pertain to systems and methods that facilitate an integrated secondary switching system for a solid-state circuit breaker will now be described with reference to the drawings, where like reference numerals represent like elements throughout. The drawings discussed below, and the various embodiments used to describe the principles of the present disclosure in this patent document are by way of illustration only and should not be construed in any way to limit the scope of the disclosure. Those skilled in the art will understand that the principles of the present disclosure may be implemented in any suitably arranged apparatus. It is to be understood that functionality that is described as being carried out by certain system elements may be performed by multiple elements. Similarly, for instance, an element may be configured to perform functionality that is described as being carried out by multiple

elements. The numerous innovative teachings of the present application will be described with reference to exemplary non-limiting embodiments.

To facilitate an understanding of embodiments, principles, and features of the present invention, they are explained hereinafter with reference to implementation in illustrative embodiments. In particular, they are described in the context of an integrated secondary switching system for a solid-state circuit breaker. Embodiments of the present invention, however, are not limited to use in the described devices or methods.

The components and materials described hereinafter as making up the various embodiments are intended to be illustrative and not restrictive. Many suitable components and materials that would perform the same or a similar function as the materials described herein are intended to be embraced within the scope of embodiments of the present invention.

These and other embodiments of the integrated secondary switching system for a solid-state circuit breaker according to the present disclosure are described below with reference to FIGS. 1-7 herein. Like reference numerals used in the drawings identify similar or identical elements throughout the several views. The drawings are not necessarily drawn to scale.

Consistent with one embodiment of the present invention, FIG. 1 represents a solid-state circuit breaker 105 with an integrated secondary switching system 107 in which a secondary switch 110 turns off electronics 112 of a residential circuit breaker such as the solid-state circuit breaker 105 before a pair of opposing primary main contacts 115(1-2) are opened in accordance with an exemplary embodiment of the present invention. This reduces electrical arcing across the primary main contacts 115(1-2). By adding the secondary switching system 107 strategically positioned within the solid-state circuit breaker's 105 main mechanism 120 such that secondary switch 110 is actuated prior to the solid-state circuit breaker's 105 primary main contacts 115(1-2) opening.

In one embodiment, the solid-state circuit breaker 105 comprises the main mechanism 120 including the pair of opposing primary main contacts 115(1-2). The solid-state circuit breaker 105 further comprises the electronics 112 including semiconductors and software algorithms that control the power and can interrupt currents. The solid-state circuit breaker 105 further comprises the secondary switching system 107 including the secondary switch 110 positioned within the main mechanism 120 such that the secondary switch 110 is configured to be actuated prior to opening of the primary main contacts 115(1-2). The secondary switch 110 is configured to turn off the power to the electronics 112 of the solid-state circuit breaker 105 before the primary main contacts 115(1-2) are opened to eliminate or reduce electrical arcing across the primary main contacts 115(1-2).

The solid-state circuit breaker 105 further comprises a handle 125 that mechanically turns ON and OFF the solid-state circuit breaker 105. The solid-state circuit breaker 105 further comprises a projection 130 formed on a distal end 132 of the handle 125 to directly actuate the secondary switch 110.

Consistent with one embodiment, the handle 125 and the projection 130 comprises a glass reinforced plastic material. In accordance with one embodiment, the projection 130 is shaped in an elongated shape with a tip 150 (as seen in FIGS. 5, 6) to change a state of the stationary switch 110 from one state to another state.

According to one embodiment, the secondary switch 110 is a micro switch with two states of operation including an ON state and an OFF state. The micro switch has an ON-OFF button 135 (as shown in FIG. 6) pivotally mounted to operate a switching mechanism (not seen) of the secondary switch 110.

The projection 130 is directly facing the ON-OFF button 135 and is positioned near the ON-OFF button 135 to operate the secondary switch 110 in the ON state and in the OFF state by pressing on it and applying an actuation force sufficient to change a state of the secondary switch 110.

When the handle 125 is moving to an OFF position the secondary switch 110 is actuated while the primary main contacts 115(1-2) are still closed. When the handle 125 is in an ON position the secondary switch 110 is in the ON state while the primary main contacts 115(1-2) are closed. When the handle 125 is in an OFF position the secondary switch 110 is in the OFF state while the primary main contacts 115(1-2) are opened.

In operation, movement of the handle 125 moves the projection 130 as it is an integral part of it thus causes the tip 150 to strike or press the ON-OFF button 135. Actuation of the ON-OFF button 135 causes the secondary switch 110 to change its state from ON to OFF or OFF to ON. The secondary switching system 107 is positioned before in a line of order of operation within the solid-state circuit breaker's 105 main mechanism 120 such that the secondary switch 110 is actuated prior to the solid-state circuit breaker's 105 primary main contacts 115(1-2) opening. In other words, that secondary switch 110 is operated first before the primary main contacts 115(1-2) are operated. This timing sequence of operation between the secondary switch 110 and the primary main contacts 115(1-2) ensures the electronics 112 are turned off before the primary main contacts 115(1-2) gets opened by the main mechanism 120.

Referring to FIG. 2, it illustrates the solid-state circuit breaker 105 with the handle 125 in an ON position in accordance with an exemplary embodiment of the present invention. The primary main contacts 115(1-2) are closed. The secondary switch 110 is in the ON state.

Turning now to FIG. 3, it illustrates the solid-state circuit breaker 105 with the handle 125 moving to an OFF position in accordance with an exemplary embodiment of the present invention. When the handle 125 is moving to an OFF position the secondary switch 110 is actuated while the primary main contacts 115(1-2) are still closed.

FIG. 4 illustrates the solid-state circuit breaker 105 with the handle 125 in the OFF position in accordance with an exemplary embodiment of the present invention. When the handle 125 is in an OFF position the secondary switch 110 is in the OFF state while the primary main contacts 115(1-2) are opened.

As seen in FIG. 5, it illustrates the projection 130 integrally formed on the handle 125 to actuate the secondary switch 110 with an actuation force in accordance with an exemplary embodiment of the present invention. The secondary switch 110 is shown in a closed state. In the closed state, the secondary switch 110 is turned ON and the electronics 112 are turned OFF.

As shown in FIG. 6, it illustrates the projection 130 integrally formed on the handle 125 such that when the handle 125 moves the projection 130 simultaneously moves an equidistance in accordance with an exemplary embodiment of the present invention. The secondary switch 110 is shown in an open state. On a line of movement sequence, the

secondary switch 110 gets operated by the projection 130 first before a contact arm will open the primary main contacts 115(1-2).

In FIG. 7, it illustrates a schematic view of a flow chart of a method 700 of turning off the electronics 112 of the solid-state circuit breaker 105 before the pair of opposing primary main contacts 115(1-2) are opened in accordance with an exemplary embodiment of the present invention. Reference is made to the elements and features described in FIGS. 1-6. It should be appreciated that some steps are not required to be performed in any particular order, and that some steps are optional.

The method 700 comprises a step 705 of providing the main mechanism 120 including the primary main contacts 115(1-2). The method 700 further comprises a step 710 of providing the electronics 112 including semiconductors and software algorithms that control the power and can interrupt currents. The method 700 further comprises a step 715 of providing the secondary switching system 107 including the secondary switch 110 positioned within the main mechanism 120 such that the secondary switch 110 is configured to be actuated prior to opening of the primary main contacts 115(1-2). The secondary switch 110 is configured to turn off the power to the electronics 112 of the solid-state circuit breaker 105 before the primary main contacts 115(1-2) are opened to eliminate or reduce electrical arcing across the primary main contacts 115(1-2).

The method 700 further comprises a step of providing a handle that turns ON and OFF the solid-state circuit breaker. The method 700 further comprises a step of providing a projection formed on a distal end of the handle to directly actuate the secondary switch.
